UNITED STATES PATENT OFFICE

CLARENCE C. CROWDER, OF BIG LAKE, TEXAS

DOOR HOOK

Application filed October 25, 1929. Serial No. 402,428.

This invention relates to door hooks and more particularly to devices of this character which are specially useful in connection with sliding doors wherein a pair of doors are shifted horizontally into abutting edge relation, although it is to be understood that this device may be used in any other way for which it may be found adapted.

An important object of the invention is to provide, in a manner as hereinafter set forth, a hook of the aforementioned character which embodies means for either rigidly or resiliently connecting the doors together to prevent said doors from being opened.

Other objects of the invention are to provide a hook of the aforementioned character which will be simple in construction, strong, durable, efficient in its use and which may be manufactured at low cost.

Other objects and advantages of the invention will become apparent from a study of the following specification, taken in connection with the accompanying drawing, wherein like reference characters indicate corresponding parts throughout the several views, and

Figure 1 is a side elevation of a door hook or latch constructed in accordance with this invention, the same being shown in operative position on the doors,

Figure 2 is a top plan view thereof,

Figure 3 is a longitudinal vertical section taken centrally through the device.

Referring to the drawings in detail the reference character 1 designates a tubular casing having an integral end closure 2 provided with a longitudinally extending opening 3 for the reception of the shank of a swiveled eyebolt 4 having the retaining head 5 on its inner end.

The swiveled eye 4 has connected therewith a loop 6 which is pivotally connected in the rectangular metallic plate 7 which in turn is secured on the door 8.

The forward end of the casing 1 is open, as clearly seen in Figure 3 and is externally threaded for the reception of a closure cap 9. The cap 9 is provided with a longitudinally extending opening therethrough for

the passage of the shank portion 10 of a hook 11.

The shank 10 extends longitudinally into the bore of the casing 1 and is provided at its inner end, with an enlarged head 12. A compressible coil spring 13 encircles the enclosed portion of the shank 10 and has its opposite end engaged against the head 12 and the inner wall of the cap 9.

The hook 11 is adapted for engagement in the eyebolt 14 which is anchored in the door 15 and the doors are thus resiliently held in their closed position, as will be apparent. When so connected together, the doors will be prevented from moving away from each other by gravity due to unevenness in supporting tracks therefor or from any other cause but same may be easily unlatched from the opposite side of said doors by a person wishing to pass therethrough by simply forcing the doors apart against the tension of the coil spring 13 and inserting the hand or a suitable implement therebetween and disengaging the hook 11 from the eye 14.

The casing 1 is provided, intermediate its ends, with a vertically extending perforated ear 16 having a horizontally disposed hook 17 pivotally connected thereto and adapted to engage in an eye 18 on the bent portion of the hook 11 for the purpose of retaining said hook 11 in its retracted position in the casing 1.

In this way a means is provided for rigidly securing the doors in closed position when it is desired to prevent entrance therethrough from the other side. It will be readily apparent that the hook 17 will prevent the hook 11 from being extended in the housing 13.

It is to be understood of course that a single sliding door may be secured by this device in an equally satisfactory manner and in this case the eyebolt 14 would be secured at a suitable place in the relatively stationary door frame, as will be understood.

It is believed that the many advantages of a door hook constructed in accordance with this invention will be readily understood, and although the preferred embodiment of the invention is as illustrated and described,

it is to be understood that changes in the details of construction may be had which will fall within the scope of the invention as claimed.

5 Having thus described my invention, what I claim as new is:

1. A door hook of the character described comprising a tubular casing, means for connecting said casing to a door, an extensible hook slidably mounted in said casing and extending forwardly therefrom, resilient means for normally retaining the hook in retracted position in the casing, and means mounted on said casing and engageable with 10 the hook for positively retaining said hook in its retracted position.

2. A door hook of the character described comprising a tubular casing, means for mounting said casing on a support, an extensible hook mounted for longitudinal movement on the casing, an expansible coil spring mounted in the casing and normally retaining the extensible hook in its retracted position in the casing, an eye mounted on 20 the hook, and a second hook pivotally anchored to the casing for engagement in the eye for positively retaining the first named hook in retracted position in said casing.

3. A door hook of the character described comprising an elongated tubular casing, means for pivotally mounting said casing on a support, a forwardly projecting extensible hook slidably mounted for longitudinal movement in the casing, said hook 30 having an elongated shank protruding into the bore of the casing, a head on the inner end of the shank, a coil spring encircling the shank and having one end in engagement with the head and its opposite end in 35 engagement with the casing for resiliently retaining the extensible hook in retracted position in said casing, an upstanding perforated ear mounted on the casing, a hook pivotally connected to said ear, and an eye 40 on the forwardly extending hook for the reception of the second named hook for positively retaining said first named hook in its retracted position.

4. A door hook of the character described comprising an elongated tubular casing open at one end, said open end being exteriorly threaded, means for pivotally connecting said casing to a support, a closure cap threaded on the open end of the casing, a 50 longitudinally extensible hook slidably mounted in the closure cap and extending into the casing, a head on the inner end of the hook, a compressible coil spring encircling the enclosed portion of the hook and 55 having one end in engagement with the head and the other end in engagement with the closure cap, a laterally projecting perforated ear mounted on the casing, a hook pivotally connected in said ear, and an eye rigidly mounted on the forward portion of the 60

first named hook for the reception of the second named hook for providing means for positively retaining said first named hook in its retracted position in the casing.

In testimony whereof I affix my signature. 70
CLARENCE C. CROWDER.
